CHUSETTS, A CORPORATION OF MASSACHUSETTS.

LOOM FOR WEAVING DOUBLE-PILE FABRICS.

1,265,084.

Specification of Letters Patent.

Patented May 7, 1918.

Application filed February 9, 1917. Serial No. 147,691.

To all whom it may concern:

Be it known that we, GEORGE F. HUTCHINS and HECTOR LE DOUX, citizens of the United States, both residing at Worcester, in the county of Worcester and State of Massachusetts, have invented a new and useful Loom for Weaving Double-Pile Fabrics, of which the following is a specification.

This invention relates to a loom for weaving double pile fabrics, the loom being particularly designed for the manufacture of cocoa fiber door mats. The material from which such mats are manufactured is peculiarly stiff and unwieldy and special constructions have been found necessary in order to successfully weave such material in power looms.

The general object of our invention is to improve the construction of looms of the class described, combining simplicity of mechanism with increased efficiency of operation.

With this general object in view, one feature of our invention relates to the provision of special mechanism and a novel method of operation by which material of the nature above described may be more effectively beaten up to form a satisfactory fabric, with particular reference to the formation of a firm selvage thereon.

Another feature of our invention relates to the provision of improved mechanism for positively actuating the shuttles so that they will follow a predetermined but irregular cycle of movements.

A further feature of our invention relates to the provision of mechanism for positively actuating the lay in an irregular manner so that it may coöperate with the irregular movements of the shuttles.

Our invention further relates to certain devices, arrangements, and combinations of parts which will be hereinafter described and more particularly pointed out in the appended claims.

A specific form of our invention and a modification thereof are shown in the drawings in which,

Figure 1 is a front elevation of one form of our improved loom, parts of the frame being shown in section, the view being taken substantially on the line 1—1 in Fig. 2;

Fig. 2 is a transverse vertical sectional view taken on the line 2—2 in Fig. 1;

Fig. 3 is a view similar to Fig. 2 but showing the parts in a different position;

Figs. 4 and 5 are an elevation and a top plan view respectively of the mechanism for releasing the shuttles from their plungers;

Fig. 6 is a plan view of a type of fabric for the weaving of which this form of our invention is especially adapted;

Fig. 7 is a similar view showing the fabric as it would appear if certain of our improvements were omitted from the loom;

Fig. 8 is an enlarged longitudinal section of the fabric;

Fig. 9 is a front elevation of a modified form of our invention;

Fig. 10 is a side elevation of the cams for actuating the lay in this form of our invention, and

Fig. 11 is a section of the fabric to be woven thereon.

Referring to Figs. 1 to 8, the loom is provided with the usual frame 10 supporting the rock shaft 11 upon which the lay 12 is pivotally supported by the swords 13. The lay 12 carries the usual reed 14 and hand rail 15. A pair of positively operated shuttles 16 are movably mounted upon the lay, said shuttles being detachably connected to plungers 17 by which they may be reciprocated. The plungers 17 are secured at their rear ends to a head 18 slidably mounted on the lay, the plungers being supported intermediate their ends upon guide rolls 19.

A flexible driving member or chain 20 has its two ends secured to the sliding head 18, the portion of the chain intermediate the ends passing around a plurality of guide pulleys 21 and also encircling a pulley 22 with which the chain has positive driving engagement. The pulley 22 is rotatable upon a fixed stud or shaft 23 and is provided with a pinion 24 meshing with a segment gear 25 pivoted to the loom frame at 26. The mechanism for angularly moving the segment gear 25 and thereby reciprocating the shuttles will be hereinafter described.

The main driving shaft 30 is supported in suitable bearings in the loom frame and is rotated at constant speed by any suitable driving mechanism (not shown). The lay is reciprocated by connecting rods 31 pivoted at one end to the lay swords and at the opposite end to upwardly extending arms forming a part of and movable with a

three-armed lever 32 pivotally mounted at 33 upon the loom frame.

A downwardly and rearwardly extending arm 32^a of the lever 32 carries a cam roll 34 positioned to engage an irregular face cam 35 mounted upon the cam shaft 30. The third arm 32^b of the lever 32 carries a cam roll 36 positioned for engagement by an intermittently operating cam 37 fixed to the shaft 30. The cam 35 operating through the cam roll 34 is effective to force the lay forward, the rearward movement of the lay being largely caused by heavy springs 38 connected at one end to the lay swords 13 and at their rear ends to brackets 38 mounted upon the loom frame.

As the stiff nature of the material to be woven causes a tendency for the reed 14 to bind after the filling has been beaten up, the cam 37 is provided to positively start the lay and reed rearwardly at the beginning of its backward stroke, the movement being thereafter controlled by the cam 35 and the roll 34, the roll being kept in close engagement with the cam by the springs 38.

The shaft 30 carries a beveled gear 40 meshing with a similar gear 41 mounted upon a forwardly extending shaft 42. An intermittent gear 43 is fixed to the shaft 42, said gear meshing with and driving an intermittent pinion 44 rotatable upon a fixed stud 45. The pinion 44 carries a crank arm 46 having a crank pin 47 to which is pivotally connected a horizontally extending rod 48. At its right hand end the rod 48 is pivotally and adjustably connected to the segment gear 25 previously described.

The warp from which the fabric is woven comprises a plurality of pile warps P, binder warps B, and selvage warps S. These warps are taken from spools carried by a creel (not shown) and are controlled by harnesses H operated in the usual manner by any suitable harness mechanism (not shown). A plurality of horizontally extending separator bars 49 are supported at their front ends upon a cross beam 50, said bars extending rearwardly between the upper and lower pile fabrics and being supported at their rear ends by vertically extending fixed bars 51. The bars 49 are provided with openings 52 intermediate their ends through which a knife 53 may be reciprocated by any suitable mechanism (not shown) to cut the pile and separate the two portions of the double pile fabrics.

The upper fabric is thereafter carried around the take up roll 54 and guide roll 55 and the lower fabric around the take-up roll 56 and guide roll 57, the fabrics being thereafter disposed of in any convenient manner.

To permit the periodical engagement and disengagement of each plunger 17 with its shuttle 16, I provide the construction shown

in Figs. 4 and 5. Each plunger 17 is provided with a flat arrow-shaped head 60 having a recess 61 positioned for engagement by a hook 62 pivoted at 63 in the end of the shuttle 16. The hook is yieldingly held in engagement with the head 60 by a spring 64 engaging the inner side of the rear arm of the hook. The front side of said arm is engaged by a relatively weaker flat spring 65 mounted in the outer side of the shuttle. 75

As the lay comes forward on the beat-up, the flat spring 65 is engaged by a spring-pressed roller 66, which overcomes the spring 64 and thus releases the plunger 17.

The roll 66 may be mounted on the breast beam or other fixed part of the loom. Other suitable devices for engaging and releasing the shuttle may be substituted if desirable.

Having thus described the construction of the essential features of one form of our invention, we will now describe its peculiar method of operation, starting with the shuttles in the position shown in Fig. 1.

In this position the pile and binder warps extend from the fabric to the harnesses as shown in Fig. 2. The intermittent pinion 44 is then given a partial revolution by the continuous rotation of the intermittent gear 43, causing the crank 46 to swing the segment gear 25 toward the left, thus moving the shuttles together through the sheds to the intermediate dotted line position designated at 16' in Fig. 1. In this position the shuttles are beyond the selvage but are not in their final positions in the shuttle boxes. While the shuttles are held in this position with the plungers 17 and the freshly inserted wefts or fillings in position within the sheds, the lay 12 is moved forward by the engagement of the cam roll 34 with the projection 35^a on the cam 35 as shown in Fig. 3. In this operation the lay is not brought to its extreme forward position but is moved far enough forward to force the pile and binder warps to the approximate position which they occupy in the finished fabric, as also clearly shown in Fig. 3. 100

The lay is then moved rearwardly a short distance or until the roll 34 engages the concentric portion 35^b of the cam 35. While the lay remains in this position the intermittent pinion 44 is caused to complete its full revolution, such movement of the pinion moving the segment gear 25 to its extreme left hand position and thereafter returning the segment gear to its initial right hand position. 115

As the gear 25 reaches its extreme left hand position, the shuttles are fully inserted in the shuttle boxes as indicated at 16'' and at the same time the plungers are disengaged from the shuttles. Therefore on the return movement of the gear 25 the plungers only will be returned to initial position leaving the shuttles in the left-hand shuttle boxes. 125 130

The supplemental movement of the shuttles to their final position is particularly designed to draw the filling tightly through the shed after the pile and binder warps 5 have been forced into approximately their final position. In this way we are enabled to secure a firm and satisfactory selvage as shown in Fig. 6, whereas if this supplemental movement were not provided, the 10 filling would form open loops at the right hand edge of the fabric as indicated in Fig. 7, these open loops absolutely preventing the formation of a firm and tightly woven selvage.

15 The cam roll 34 thereafter engages the projection 35^c upon the cam 35, this projection being somewhat greater than the projection 35^a and forcing the lay 12 to its extreme forward or beating-up position. The 20 cam roll 34 is then forced backward until it engages the smaller concentric portion 35^d of the cam 35, the lay 12 then occupying its extreme rear position as shown in Fig. 2. During the final forward movement of the 25 lay and its subsequent withdrawal, a part of the harnesses are shifted to carry certain of the binder warps to the opposite shed, the pile warps however remaining in the same position.

30 At the commencement of the rearward movement one of the cam surfaces or projections upon the cam 37 engages the roll 36 to positively force the lay rearwardly. This positive actuation is made necessary by the 35 stiff heavy warp which has a strong tendency to bind in the reed.

With the lay in its rearmost position the intermittent pinion is given a complete revolution thus moving the gear 25 first to its 40 left hand position thereby carrying the plungers through the shed to again engage the shuttles and thereafter withdrawing the plungers with the shuttles, thus returning the latter to their initial position.

45 The lay is then again moved forward to beat in the filling through the engagement of the roll 34 with the projecting portion 35^e of the cam 35, the lay being thereafter immediately returned to rearward position as 50 the roll 34 is forced into engagement with a second concentric portion 35^f of the cam 35. At the commencement of this rearward stroke the second projection upon the cam 37 engages the cam roll 36 to positively start 55 the rearward movement of the lay.

During the last described forward and rearward movement of the lay, the harnesses are again shifted to change the remaining binder warps and also the pile warps to the 60 opposite shed. The parts are then in their original positions, with the exception of the interchange of warp threads, and the cycle of operation may be repeated.

The difficulty in forming the selvage is 65 occasioned very largely by the pile warps

which are much heavier and stiffer than the binder and selvage warps. By beating up the filling and plungers together and thereafter tightening the filling, we secure a satisfactory selvage on one edge of the mat fabric. 70

As the pile warps are not crossed while the shuttles are in the left hand boxes, the pick of filling inserted as the shuttles are returned to the right hand boxes is easily beaten in against the few binder and selvage 75 warps which have changed shed. Thus a good selvage is assured on the second edge of the fabric.

By the use of the modified construction shown in Figs. 9 and 10, we are able to 80 simplify the weave by providing an additional pair of plungers 170 at the left-hand side of the loom and by duplicating certain parts of the actuating mechanism for the plungers. While this modification increases 85 the number of operating parts, it avoids the idle movement of the plungers in passing back through the warp to make connection with the shuttles when they are at the left hand side of the loom, and it produces the 90 plain double fabric shown in Fig. 11. The construction and operation of this form of our invention will be clearly apparent, as the additional mechanism substantially duplicates that already described. 95

The actuating mechanism for the additional plungers 170 comprises a head 180 slidably mounted on the lay 120 and connected to a flexible driving member or chain 200 supported on suitable guide pulleys and 100 positively driven by the pulley 220. The pulley 220 is provided with a pinion 240 meshing with a segment gear 250.

An intermittent gear 430 is mounted on the shaft 42, the driving mechanism for said 105 gear being the same as that previously described for the gear 43. The gear 430 meshes with an intermittent pinion 440 mounted on a fixed stud 450 and having a crank arm 460 with a crank pin 470 which is 110 connected to the segment gear 250 by a link or rod 480. The stud 450 for the pinion 440 is diametrically opposite the stud 45 on which the pinion 44 rotates.

The cams 35 and 37 in Figs. 2 and 3 are 115 replaced by cams 350 and 370 shown in Fig. 10, in which the opposed halves of each cam are duplicates. The remaining parts of the loom are substantially identical with those already described with the exception that 120 the plungers 17 and 170 merely enter recesses in the ends of the shuttles, but are not latched therein, as each plunger is used merely to push its shuttle to the opposite side and is not used to move the shuttle on 125 its return flight.

We will now describe the operation of this form of our invention. Starting with the shuttles at the right side of the loom, as shown in Fig. 9, the pinion 44 is partially 130

rotated, acting through the segment gear 25, pinion 24, pulley 22 and chain 20 to force the shuttles across the loom to the position shown in dotted lines on the left-hand side 5 of the loom. A dwell portion of the gear 430 then holds the plungers in this position while the lay is forced forward by engagement of the roll 34, with the projection 350^a of the cam 350, partially beating up the filling and the plungers 17. The lay is then slightly withdrawn, as the concentric portion 350^b of the cam 350 engages the roll 34, and at the same time the revolution of the pinion 44 is completed. This movement of 10 the pinion first completes the advance of the plungers 17 and places the shuttles fully in the left-hand shuttle boxes, and then withdraws the plungers. The engagement of the roll 34 by the projection 350^c of the cam 350 15 then moves the lay to its extreme forward position, thus beating up the inserted filling. The lay then moves rearward under the combined action of the springs 38 and the cam 370. All warps are then shifted, and the intermittent gear 430 next engages the gear 440, repeating the operations above outlined with the plungers 170 forcing the shuttles to the right-hand side of the loom but short of their final position, partially beating up the 20 filling together with the plungers 170, thereafter boxing the shuttles and withdrawing the plungers, and then beating up the filling to its final position. The cycle of operation is thus completed and the parts are returned 25 to their first position.

The use of two sets of plungers enables us to partially beat up each pick of filling and to thereafter tighten the filling before it is finally beaten up, thus giving us a satisfactory selvage on both edges without the idle return shot of filling.

Having thus described our invention it will be evident that other changes and modifications can be made therein by those skilled 45 in the art without departing from the spirit and scope thereof as set forth in the claims and we do not wish to be limited to the details herein disclosed, but what we do claim is:—

50 1. In a loom, in combination, a lay, a positively operated shuttle mounted on said lay, means to move the shuttle to insert a pick of filling in the shed, means to advance the lay to partially beat up the inserted filling, means to move the shuttle to tighten the inserted pick of filling, and means to thereafter move the lay to fully beat up said filling.

60 2. In a loom, in combination, a lay, a shuttle, a plunger for positively moving said shuttle, and operating mechanism for moving said plunger and lay, said mechanism being effective to cause said lay to beat up a pick of filling with said plunger in the warp shed and without change of shed, and to

thereafter beat up the same pick with said plunger withdrawn, at substantially the same time changing certain of the warp threads from one shed to the other.

3. In a loom, in combination, a lay, a positively-operated shuttle mounted on said lay, means to move said shuttle to a predetermined intermediate position beyond the selvage, in which position said shuttle temporarily remains, means to beat up the filling without changing the warp shed while the shuttle is in such intermediate position, means to thereafter move said shuttle to extreme position, and means to beat up the same filling a second time.

4. In a loom, in combination, a lay, a positively-operated shuttle mounted on said lay, means to move said shuttle to a predetermined intermediate position beyond the selvage, means to thereupon beat up the filling without changing the warp shed, means to move said shuttle to extreme position, and means to beat up the same filling a second time, said shuttle-moving means comprising an intermittent pinion and a continuously rotating intermittent gear meshing therewith, said gear giving said pinion a positive, irregular cycle of operation.

5. In a loom, in combination, a lay, a positively-operated shuttle mounted on said lay, means to move said shuttle to a predetermined intermediate position beyond the selvage, means to thereupon beat up the filling without changing the warp shed, means to move said shuttle to extreme position, and means to beat up the same filling a second time, and on the same beat to change certain of the warp threads from one shed to the other.

6. In a loom, in combination, a lay, a positively-operated shuttle, means to move the shuttle, and means to move the lay to beat up the filling, said means being effective to cause alternate picks of filling to be beaten up twice in succession and to cause the remaining picks of filling to be beaten up once only.

7. In a loom, in combination, a lay, a shuttle, means to move said shuttle positively, means to give the lay a partial and a complete forward movement successively after the insertion of each alternate pick of filling only, and means to beat up the intervening picks of filling with a single advance movement of the lay.

8. In a loom, in combination, a lay, a pair of shuttles mounted on said lay, a plurality of harnesses carrying binder, selvage, and pile warps, means to positively move said shuttles to an intermediate position beyond the selvage, means to move said lay to beat up the filling with the shuttles in intermediate position and without change of warp shed, means to move said shuttles to extreme position, means to thereupon move said lay to

beat up said filling a second time and on the same beat to change certain of the binder and selvage warps only from one shed to the other, means to return said shuttle to initial 5 position, and means to thereupon move said lay to beat up the filling last inserted and on the latter beat to change the pile warps and the remaining binder and selvage warps from one shed to the other.

10 9. In a loom, in combination, a lay, a shuttle, means to move the shuttle, means to give the lay a partial and a complete forward movement successively after the insertion of a pick filling in the shed, and 15 means to tension the inserted filling between said movements, said lay-actuating means including two continuously rotating cams each provided with a plurality of successive operative projections, one cam being effective to move said lay positively in the forward direction and the other cam to move the lay positively in the rearward direction.

20 10. In a loom, in combination, a lay, a shuttle, means to move the shuttle, and 25 means to give the lay a partial and a complete forward movement successively after the insertion of a pick of filling in the shed, said means including two continuously rotating cams each provided with a plurality 30 of successive operative projections, one cam being effective to move said lay positively in

the forward direction and the other cam to move the lay positively in the rearward direction, and tension devices also effective to move said lay rearwardly.

11. The method of weaving which consists in inserting a pick of filling in a warp shed, beating up said filling without changing the shed, applying tension to said filling in the direction in which it was inserted to tighten 40 said filling in the shed, and thereafter beating up said filling a second time and on the same beat changing certain of the warp threads to the other shed.

12. The method of weaving which consists in inserting a pick filling in a warp shed by forcing a shuttle through said shed by means of a plunger, beating up said pick of filling together with the plunger by which it was inserted without change of warp 50 shed, giving the shuttle an additional movement in the same direction to tighten the filling, withdrawing said plunger and thereafter beating up said filling a second time with the plunger removed from the shed 55 and on the same beat changing certain of the warp threads to the opposite shed.

In testimony whereof we have hereunto affixed our signatures.

GEORGE F. HUTCHINS.
HECTOR LE DOUX.
